Att. for

Des. 1310

John D. Cunningham, of Franklin, Tennessee,
Letters Patent No 1310. Dated Aug. 14. 1860.

The schedule referred to in these Letters Patent and making part of the same.

To all whom it may concern:

Be it known that I, John D. Cunningham, of Franklin
in the County of Williamson, and State of Tennessee, have invented and produced
a certain new design for Coffins, and I hereby declare that the annexed drawings
fully and clearly represent my said design.

The top and bottom of this Coffin are made in the form herein
